UNITED STATES PATENT OFFICE.

ANDREW F. WINTERCORN, OF CHICAGO, ILLINOIS.

ENGINE-COOLING SYSTEM.

Application filed September 11, 1924. Serial No. 737,195.

This invention relates to an improved engine cooling system wherein the engine is provided with less cooling for operation in cold weather or in a cold climate, and more cooling for operation in warm weather or in a warm climate. Thus the invention provides an engine having air cooling fins of a number and size to give sufficient cooling for operation in the cold months when water would be apt to freeze, and having in addition to the air-cooling fins that would by themselves be inadequate for cooling in the warm months, means for water cooling which provides circulating cooling fluid about the cooling fins, the obvious purpose in the foregoing provisions being to utilize each of the two types of cooling in the seasons where they are most advantageous and of least disadvantage.

One of the principal objects of the invention consists in providing an engine having air-cooling fins for air-cooling in cold weather, and having a sheet metal enclosing jacket to provide water-cooling in warm weather, which is arranged to be kept on always or, if desired, removed and kept off in cold weather, the purpose being to secure only air cooling in cold weather where less cooling is needed and to secure the additional cooling effect of the water or other liquid cooling medium in warm weather, when more cooling is needed.

An important object of the invention relating to the engine construction involved in accomplishing the foregoing objects, consists in providing a sheet metal water jacket for enclosing finned cylinder walls, which is secured with a water tight joint in the fastening down of the cylinder head, and is at the same time connected with the cylinder head to have cooling fluid circulate therebetween.

Still another object of the invention resides in the provision on the engine of an upper annular flange and a lower annular flange above and below the cooling fins on the cylinder walls, the upper flange providing a place for attachment for the cylinder head and for securing the water jacket into connection with the cylinder head, while the lower flange provides a place for the attachment and sealing of the lower end of the water jacket and also a convenient place for a permanent water jacket hose connection.

The foregoing and other objects of the invention are set forth in the following de-

tailed description in which reference is made to the accompanying drawing illustrating the invention.

Fig. 1 of the drawing is a cross section through one cylinder of an engine constructed in accordance with the invention.

Fig. 2 is a diagrammatic view in side elevation of the improved cooling system.

Air-cooled engines of the present standard form are designed to approach, as nearly as possible, proper cooling in warm weather, and when so designed have been found to be overcooled in cold weather, or where a medium is struck, the cooling is not sufficient in warm weather and usually excessive in cold weather, so much so that it is commonly known that air-cooled engines quickly overheat in the summer and commence to knock if operated under even a momentary heavy load. They are further known to be subject to the objection of being overcooled in the winter months to an extent that there is an appreciable loss of economy. Furthermore, these engines are notorious for being hard to start in cold weather when designed to operate the year around with air-cooling.

Water-cooled engines on the other hand are designed to secure average good performance in warm weather. However, in cold weather the engine is overcooled and there is a resultant loss of economy. Besides, there is the ever present danger of freezing which may cause serious damage either to the engine or the radiator. This danger is present even where alcohol and other so-called non-freeze solutions are used, since these pass off at low temperatures giving a characteristic foul odor, and the motorist can never be certain that the concentration of non-freezing solution is sufficient to prevent freezing.

In the absence of the use of non-freezing solutions, it is of course necessary to drain the system where the car is left standing for even a short time. When no anti freeze solution is used there is danger of freezing even while the car is in operation. This usually occurs in the lower hose connection where the water in the radiator is at the lowest temperature.

The present invention aims to avoid as far as possible the disadvantages in each of the above mentioned systems, while retaining as far as possible the advantages. Thus the invention provides air-cooling in cold weather when it is of decided advantage not to have to use a freezable circulating cooling

liquid such as water, and provides water-cooling in warm weather at which time it is not a serious inconvenience, particularly since there is no possibility of the water freezing. The invention provides air cooling means designed with special reference only to cold weather operation, no special concern being given the matter of warm weather operation, since at that time the cooling is augmented by water circulating about the air cooling fins. With this arrangement, only a relatively small amount of cooling fluid is required since especially good cooling is secured through the transmission of heat from the cylinder walls to the circulating water by the cooling fins. The manner of application of the invention is incidentally of advantage where the jacket is removed in that it necessitates the removal of the cylinder head at least once a year, when the jacket is removed or replaced. This affords an opportunity for inspection of the valves and cylinder walls and for the removal of the carbon present. The added operation involved in removing the water jacket or replacing the same as the case may be, is hardly of any consequence, being far less involved than the removal or replacement of the cylinder head itself and being actually only an incident to that operation.

Referring now to the drawing, the engine cylinder 1 illustrated, may be one of a group of cylinders cast en bloc, or may be a separately cast cylinder. However, for convenience, the invention is illustrated in Fig. 2 as applied to an engine having the cylinders cast together and fastened as a unit on the crankcase 2. The piston 3, connecting rod 4, and crankshaft 5 shown are entirely conventional. The head 6 has valve cages 7 secured therein in the usual manner as illustrated. The valves 8 operating in the cages 7 are opened by the rockers 9, in turn operated by push rods 10, all being of a conventional form. In order to facilitate the application of the water jacket shown at 11, the spark plug 12 is mounted in a recess 13 in the head 6, and the intake manifold 14 and exhaust manifold 15 are supported solely from the head. Thus, in the application of the water jacket, there is avoided the necessity of fitting the jacket about spark plug openings and the like, since these all occur in the head. Also, while the invention is intended for general application to all types of engines, it is most conveniently applicable to engines of the overhead valve type, as will be apparent on inspection.

The water jacket 11 is suitably of sheet metal, such as copper or other non-corrosive metal, capable of being brought to the form of the jacket illustrated. The jacket fits down over the engine block over the edges of an annular flange 16 thereon. The top wall 17 of the jacket has openings 18 to

register with the bores of the cylinders and openings 19 registering with ports 20 provided in the flange 16 and ports 21 opening into the hollow cylinder head 6 from the under side. The wall 17 of the jacket 18 70 may be coated with asbestos or other suitable packing material, and faced with a thin sheet of copper or the like on both sides to furnish a gasket for the cylinder head in the manner indicated. The cylinder head 6 is 75 secured by bolts 22 to the flange, the bolts being entered through the head in the usual way. If desired, the flange may be provided of slightly greater width to have the jacket 11 bolted or otherwise secured thereto about 80 the head, the latter being fastened directly to the flange. This would obviate the necessity for removing the head when removing the jacket. The lower end of the jacket 11 is flanged outwardly as shown at 23 and rests 85 upon a lower annular flange 24 on the engine block. The flange 16 and the flange 24 are both continuous about the entire block. The flange 24 has an annular groove 25 into which the flange 23 is pressed as shown, together 90 with gasketing material similar to that under the cylinder head, by means of a frame 26 which has an annular rib 27 and is bolted as by means of bolts 28 to the flange 24. The flange 24 provides a convenient place 95 for the attachment of the lower hose connection 29. The upper hose connection 30 is fastened to the cylinder head 6 in the usual manner. From the description thus far, it will be apparent that there is no considerable 100 difficulty in applying or removing the water jacket 11 and that the construction affords a water tight joint under the cylinder head. The location of the lower hose connection 29 at the place shown obviates the necessity 105 for removing the same when the water jacket is removed. In a similar way the conventional location of the upper hose connection 30 is of advantage.

The actual additional operation involved 110 in applying or removing the water jacket, outside of the operations necessarily involved in removing the cylinder head is obviously of no considerable consequence. The jacket and its fastening means fit down over 115 the cylinder block and there is involved only a simple bolting operation. When the water jacket is removed, a conventional type gasket will be used under the cylinder head and the cylinder head bolted down to the flange 16, 120 in quite the same way as cylinder heads are ordinarily bolted down to the engine block. If desired, a separate air-cooled head may be provided to replace the head 6 when the jacket 11 is removed.

The walls of the cylinder 1 are provided with annular ribs 31 between the flanges 16 and 24. These ribs may extend continuously about the engine block and are preferably of increasing width toward the 120

top of the cylinders where there is greatest need for cooling. The jacket 11 is also enlarged at this point as shown for a similar purpose. The ribs 31 in accordance with the 5 present concept, it should be understood, need not be of a size or in numbers, such as will afford the radiating surface of an all-year around continuously operated air-cooled engine, but instead should be designed only 10 with reference to continuous operation in cold weather, preferably, water so cold that the jacket water would freeze if it were used. In warm weather, any deficiency in cooling effect is made up by the water cooling provided as above stated. The head 6 is also 15 provided with cooling fins as shown at 32 on the outside of its inner wall and preferably also about the valve cages 7. To facilitate the production of heads of this construction 20 it would perhaps be found expedient to cast the heads in upper and lower halves and weld the halves together as indicated at 33. Here again it will be understood that the ribs 32 are designed only with reference to cooling 25 the cylinder head in cold weather independently of any circulating cooling water. In warm weather the cooling effect is increased by the use of circulating cooling water, as above stated. When cooling water 30 is circulated through the jacket 11 and through the head 6 about the air-cooling fins 31 and 32, there is ideal transmission of heat from the cylinder walls and the head to the cooling water. As a result the water 35 jacket need not have the capacity ordinarily required in conventional water cooled engines, nor need the jacket be as elaborate in construction. It will be understood that at all times the usual cooling fan 34 provided 40 between the radiator 35 and the engine may be kept in operation.

In operation, the motorist will ordinarily keep the jacket filled with water until there is actual danger of the water freezing. If 45 he desires to dispense with the advantages the invention affords of the use of the air-cooling for such time he may leave the water in the jacket and observe the usual precautions against freezing. Where the cold 50 weather is at all persistent, or when the car is to be used to any great extent, it is obviously of considerable advantage to be able to rely only on air cooling and dispense with the bother and worry going with the 55 use of the water cooling. On the other hand it will be understood that the jacket may be removed and the air-cooling will be ordinarily adequate for even continuous operation in moderately cool weather without having to replace the jacket for water cooling. 60

It will be seen that in winter the water

may be drained from the radiator and the 65 hose connections opened. The air-cooling may then be afforded simply by the air entering the lower opened hose connection and leaving the upper opened hose connection. Or, if so desired, a blower fan operated from the engine may furnish a forced draught through the lower hose connection. Under 70 such conditions, the only difference in the cooling in the different seasons is the use of water instead of air circulating about the air-cooling fins. It will be seen that a car having a water pump driven from the engine on a countershaft may be provided, on the 75 same shaft preferably with a fan having a detachable coupling connection to be operated, when the pump is disconnected. Thus there would be involved only a simple interchanging of the lower hose connection from 80 the water pump to the fan or vice versa accompanied with the coupling of the fan and the uncoupling of the pump or vice versa as the case may be.

While I have described the invention as 85 applied to a specific embodiment it is to be understood that it is not so limited but is capable of considerable modification, and that all adaptations and modifications coming within the spirit and scope of the invention are to be understood as covered by the appended claims, excepting only in so far as the prior art may limit their construction. 90

I claim:

1. An engine comprising a cylinder having air-cooling fins, a water jacket removably enclosing the same, and a removable head having a water jacket to cooperate with said cylinder jacket, said head being air-cooled 100 when said cylinder jacket is removed. 95

2. In an internal combustion engine, a convertible air or water cooled cylinder provided with fins sufficient to effect air cooling of the cylinder under low temperature weather conditions, and a removable jacket enclosing said cylinder and fins and provided with water circulating connections, for use 105 under high temperature weather conditions.

3. In an internal combustion engine, a convertible air or water cooled cylinder provided with fins sufficient to effect air cooling of the cylinder in extremely cold weather, and a jacket enclosing said cylinder and fins and provided with inlet and outlet connections adapted for the circulation of water 110 through the jacket about the cylinder and fins for the cooling of the cylinder in warm weather or moderately cold weather. 115

In testimony whereof I affix my signature.

ANDREW F. WINTERCORN.
